ATTORNEY.

UNITED STATES PATENT OFFICE.

NORMAN E. BENSINGER, OF CHICAGO, ILLINOIS.

CUE-TIP.

1,390,331.

Specification of Letters Patent. Patented Sept. 13, 1921.

Application filed November 28, 1919. Serial No. 341,038.

To all whom it may concern:

Be it known that I, NORMAN E. BEN-SINGER, a citizen of the United States, residing at Chicago, in the county of Cook and 5 State of Illinois, have invented a new and useful Cue-Tip, of which the following is a specification.

My invention relates to improvements in cue tips, to which I apply a cream to the 10 leather element of the tip.

An object of my invention is to provide a tip that will not miss-cue nor require frequent chalking, but on the contrary it will retain its chalk notwithstanding this impact 15 caused by the frequent striking engagements of the cue tip with the cue ball.

Another object of my invention is to devise a cue tip that will not only hold fast to the cue or ferrule, and thereby obviate the necessity of frequently replacing the tip, but it 20 will also be easily attached to the cue in the first instance.

Another object of my invention is to provide a cue tip, that although it is saturated 25 with cream—chalk applied for playing billiards will not entirely lose its chalky properties, but will, for practical purposes retain them.

A construction and means by which I accomplished these results will become more 30 apparent upon a perusal of the accompanying specification and drawing in which:

Figure 1 is a cross-sectional view taken 35 through a piece of leather, with a piece of fiber attached.

Fig. 2 shows shallow diagonal incisions cut in a piece of fiber.

Fig. 3 shows a fragmental view of the cue, 40 with the untrimmed cue tip attached to the ferrule.

Fig. 4 shows a fragmental view of the cue, with the completed cue tip attached.

In order to carry out my invention or discovery, I take a large flat piece of chrome 45 tanned leather (5) of sufficient thickness, usually varying from $\frac{1}{4}$ to $\frac{5}{16}$ of an inch. I then place the leather on a flat surface, with its smooth or glossy side, as it is commonly called, down. Next I take a quantity 50 of cream (the oily unctuous substance of a yellow color, which forms on the top of milk when it stands in a cold place), and apply a coat of it to the rough side (6) of the leather. After having permitted it to stand 55 for a while, I then give it another coat of the cream and sometimes a third coat, de-

pending upon the quality of the leather and cream.

After it has stood for five or six hours, it becomes apparently dry to all external appearances. I then size it with glue, to prepare it for adhering to the fiber element (7) and also preventing the cream from tending to be attracted toward the fibrous member by capillary attraction, and thus leaving but one course open for it to travel, namely in a direction toward the smooth glossy or outward side (8) of the leather.

I next take a flat piece of fiber varying in thickness from $\frac{3}{16}$ of an inch to $\frac{5}{16}$ of an 70 inch, which has previously had diagonal lines (9) scratched across its entire surface at regular intervals, by means of a sharp tool; after which a fine toothed serrated tool is drawn across the scratched side, to uniformly roughen the space between the 75 scratched lines, for a purpose well known to any one versed in that art.

The connection between the roughened side of the fiber strip and the leather is accomplished by an application of any suitable cement or glue, after which the leather and fiber are held together by means of clamps until the cement or glue has set.

After preparing the leather and fiber in 85 the manner just described, I feed it into a punch press, and through the co-actions of the elements of the press, it is stamped out into disks (10) of a size suitable for attachment to the ferrule (11).

During the stamping operation while the fiber is being stamped out and simultaneously with it, a small hole (12) is stamped through the center of the fiber and into the leather a short distance, to provide a receptacle for the glue, which will act as a dowel, when the two are assembled and at the same time take up the surplus glue, that would otherwise be squeezed out between the fiber and ferrule as the clamps were applied, 100 to hold the tip and ferrule together while setting.

The hereinbefore described operation will leave the tip with the fiber between it and the ferrule as indicated in Fig. 4, securely in 105 place, but with the outer edges still not rounded, and of course as yet unsuitable for use.

After the cue tip has become permanently connected with the ferrule, it is shaped off so 110 that it will have a rounded contour and at the same time, the smooth, glossy skin of the

chrome leather will be entirely pared off, and thus permit the cream absorbed by the leather to be gradually fed to the outer surface of the tip, to act upon the chalk.

5 It has been found by experiments and experience, that after the cue has been treated as I have described it, that the chalk will adhere better and longer than by known methods, and that it will practically eliminate 10 miss-cueing. In my experiments I have tried oils, such as olive oil, corn oil and other oils for this same purpose, and found them unsatisfactory.

15 I do not wish to be confined to the exact method of preparing my cue, but to avail myself of all variations falling within the scope of the claims to my invention or discovery.

I claim:

20 1. A method of making and of securing the tip to the billiard cue including the steps of roughening the face of the fiber washer, coating the non-glossy side of the leather with cream, and subsequently sizing it and 25 cementing the roughened side of the fiber to the sized side of the cue tip.

2. The method of securing a tip to a billiard cue including the steps of drawing straight cuts in the face of the fiber washer, 30 then uniformly roughening the face of the said washer and cementing the washer to the rough side of a cue tip, said rough side having first received a plurality of coats of an unctuous substance, before being sized.

35 3. The method of making a tip for a bil-

liard cue, which consists of providing a sheet of chrome tanned leather having a plurality of coats of cream applied to the rough side, and then a plurality of coats of sizing applied, allowing the cream to dry 40 and providing a piece of fiber with the plurality of intersecting irregular grooves on one side, roughening said surface over its entire area, gluing said fiber sheet to the sized leather sheet, and punching them out to 45 gether with the tip.

4. The method of making a tip for a billiard cue, which consists of providing a sheet of fiber with the plurality of intersecting irregular grooves on one surface, 50 roughening said surface over its entire area, gluing said fiber sheet with its roughened surface to the roughened side of a sheet of cream imbued leather, punching disks out of said combined sheets, and shaping the 55 tips.

5. As a new article of manufacture a billiard cue tip, ready for attachment to a billiard cue and comprising a circular disk of fiber and a circular disk of cream imbued 60 leather, secured to said disk of fiber, both of said disks being provided with a central opening, the fiber disk having a roughened surface held to the leather disk.

In testimony whereof I affix my signature 65 in the presence of two witnesses.

NORMAN E. BENSINGER.
